UNITED STATES PATENT OFFICE.

CHARLES W. BEEHLER, OF ST. LOUIS, MISSOURI.

BOX-FASTENER.

SPECIFICATION forming part of Letters Patent No. 739,639, dated September 22, 1903.

Application filed February 9, 1903. Serial No. 142,602. (No model.)

To all whom it may concern:

Be it known that I, CHARLES W. BEEHLER, a citizen of the United States, residing in the city of St. Louis, in the State of Missouri, have 5 invented certain new and useful Improvements in Box-Fasteners, of which the following is a full, clear, and exact description, reference being had to the accompanying drawings, forming part of this specification.

10 My invention relates to an improvement on the box-fastener shown in Letters Patent issued to me October 6, 1896, No. 568,936, the object of the present improvement being to provide means by which the catch-engaged 15 spring of said fastener is securely held in the lid-plate of the fastener, so that it may not become displaced from its seat therein during the handling of the lid-plate previous to application to a box and also so that it will 20 be constantly maintained in a seat in said plate after said plate has been applied to a box.

The invention consists in features of novelty hereinafter fully described, and pointed 25 out in the claim.

Figure I is a top view of my fastener. Fig. II is a vertical section taken on line II II, Fig. I. Fig. III is a vertical section taken on line III III, Fig. II, looking in the direction 30 indicated by the arrow on said line. Fig. IV is a side elevation of the lid-plate.

A designates the front wall of a box, and B the box-lid.

1 designates a catch secured to the inner 35 face of the box-wall A and provided at its upper end with a hook-head 2, containing a seal-receiving aperture 3, the construction of said parts being substantially the same as that in my patent hereinbefore referred to.

40 4 designates the lid-plate, which is formed with a raised central portion 5, containing an aperture 6, through which the hook-head of the catch 1 passes, as in my former patent. At the front side of the lid-plate 4 is an aperture 45 seal-receiving ear 7, the opening in which registers with the aperture 3 in the catch-head after said head has passed through the aperture 6 in the lid-plate.

8 is the catch-head-engaging spring located 50 beneath the raised portion 5 of the lid-plate and having the return-bend 9, straight arm 10, and arm 11, the point 12 of which is up-

turned and engages in the aperture 13 in the lid-plate, as in my former patent. The parts of my present fastener thus far described are 55 substantially identical with corresponding parts in my previous patent to which reference has been made, and no invention *per se* is herein claimed for them.

I now come to the construction wherein my 60 present improvement resides. As will be seen on referring to my former patent, the catch-engaging spring is located in an open recess beneath the lid-plate and is not retained therein, except by the loose engagement of 65 the upturned point of one arm of said spring and the frictional contact of the spring with the lid-plate beneath the raised portion. Practical use of the fastener with the construction stated has demonstrated that the 70 construction is objectionable, inasmuch as the catch-engaging spring being seated beneath the lid-plate without means of confinement therein it is impossible to retain it assembled with the plate in the handling there- 75 of before applying the fastener to a box on which it is to be used. Furthermore, the arm of said spring that receives the engagement of the catch being unconfined whenever the lid-plate becomes loosened from the box-lid 80 at its forward side to a material degree the catch-engaging arm is permitted to pass beneath the loosened plate and projects across the catch-aperture in the lid-plate in position that prevents the passage of the catch 85 through said aperture by striking the arm to force it rearwardly previous to engaging it. For the purpose of overcoming the difficulty referred to I provide for the confinement of the catch-engaging spring 8 by extending 90 transverse supports across the plate beneath the spring at each end of the lid-plate 4 and at a lower level than the raised portion 5 or, in other words, on a plane with the base of said lid-plate. 14 designates one of these 95 cross-supports on which the return-bend end of the catch-engaging spring rests, and 15 is a support at the opposite end of the plate on which the straight arm 10 of the catch-engaging spring rests for lateral movement. 100 The support 15 is preferably made in the form of tongues, which may be bent rearwardly from the plane of the base of the lid-plate to permit the introduction of the catch-

engaging spring and thereafter bent into a plane with said plate to provide a flat surface corresponding to the opposing support 14. It will be seen that by this construction 5 the catch-engaging spring is constantly confined and held within the lid-plate at all times after its insertion either before or after the application of said plate to a box and that therefore there is no liability of its dis- 10 placement in the objectionable manner hereinbefore referred to.

I claim as my invention—

A box-fastener consisting of a catch adapted to be secured to the wall of the box, a plate

adapted to be secured to the lid of the box 15 and having a raised central portion, a catch-engaging spring located beneath said raised portion of the lid-plate, and transverse supports located beneath the level of said raised portion by which said catch-engaging spring 20 is confined in the space beneath said raised portion, substantially as and for the purpose specified.

CHARLES W. BEEHLER.

In presence of—

GEO. H. KNIGHT,
NELLIE V. ALEXANDER.
